UNITED STATES PATENT OFFICE.

EUGENE R. EDSON, OF CLEVELAND, OHIO, ASSIGNOR TO THE EDSON REDUCTION MACHINERY COMPANY, OF AUGUSTA, MAINE, A CORPORATION OF MAINE.

APPARATUS FOR DISPOSING OF FOUL GASES.

SPECIFICATION forming part of Letters Patent No. 736,946, dated August 25, 1903.

Application filed January 18, 1902. Serial No. 89,599. (No model.)

To all whom it may concern:

Be it known that I, EUGENE R. EDSON, a citizen of the United States of America, residing at Cleveland, in the county of Cuyahoga and State of Ohio, have invented certain new and useful Improvements in Apparatus for Disposing of Foul Gases and Vapors; and I hereby declare the following to be a full, clear, and exact description of the invention, such as will enable others skilled in the art to which it pertains to make and use the same.

My invention relates to improvements in apparatus for disposing of foul gases and vapors.

The object of this invention is to provide apparatus for disposing of foul or ill-smelling gases and vapors emanating or arising from material which is being dried or rendered or otherwise reduced and to avoid expelling or discharging the said vapors and gases into, and thereby contaminating, the external atmosphere and to partially utilize the said gases to advantage.

With this object in view and to the end of realizing other advantages hereinafter appearing—such, for instance, as providing an apparatus of the character indicated which is simple and durable in construction and reliable in its operation—my invention consists in certain features of construction and combinations of parts hereinafter described, and pointed out in the claim.

In the accompanying drawings, Figure I is a side elevation, partly in section, of apparatus embodying my invention and illustrates a partial utilization of the foul or ill-smelling gases and air in facilitating the combustion within a furnace wherein the said gases are consumed. Fig. II is a side elevation, largely in central longitudinal section, of the tank wherein the insoluble gases are separated from the gases or vapors which are soluble in water.

Referring to the drawings, *a* designates a tank, which is preferably in the form of a cylinder arranged in a horizontal plane. The chamber of the tank *a* is supplied with water preparatory to the operation of the apparatus, and a depth of water, having the water-level within the upper portion of the said tank, is maintained during the operation of

the apparatus. The water-inlet of the tank *a* is preferably arranged at the bottom and centrally between the ends of the tank. Preferably a pipe-fitting *b* is attached to the bottom of the tank *a* centrally between the ends of the tank and in open relation with the water-receiving chamber in the tank. A valved water-supply pipe *c* connects and is in open relation with the pipe-fitting *b* and has its valve *d* normally closed. A valved drain-pipe *e*, having its valve *f* normally closed, extends from the pipe-fitting *b* to a waste-pipe *g* and is attached to the said waste-pipe and to the said pipe-fitting. The pipe *e* is instrumental in establishing open relation between the chamber of the tank *a* and the waste-pipe *g*. The waste-pipe *g* extends above and below the drain-pipe *e*, extending downwardly below the said drain-pipe to and communicating with a pipe *h*, adapted to feed a sewer, and extending upwardly above the said drain-pipe to the top of the tank *a*, where it, the said waste-pipe *g*, communicates with the chamber of the said tank at one end of the tank and at the elevation of the level of water which is to be maintained within the tank during the operation of the apparatus.

By the construction hereinbefore described the tank *a* is supplied with water or drained, according as the valve *d* of the pipe *c*, or the valve *f* of the pipe *e*, is opened; but of course the valve *f* is only opened when the tank *a* needs cleaning internally, and sediment accumulating upon the bottom of the chamber of the tank is removed into the waste-pipe *g* through the pipe *e* upon opening the valve *f*. The foul or ill-smelling vapors and gases which are to be disposed of and to the best advantage are conducted into the body of water within the tank *a* during the operation of the apparatus, and such of the said gases and vapors as are soluble in the water are absorbed into and diffused throughout the body of water and conducted off with the water flowing into the waste-pipe *g*. The valve *d* of the water-supply pipe *c* is of course opened and left open during the operation of the apparatus, and the supply of water to the tank *a* is so regulated by the valve *d* that a continuous flow of liquid from the said tank into the waste-pipe *g* obtains during the operation

of the apparatus. Any gases or air conducted into the tank and not soluble in or conveyable off with the water flowing from the tank into the waste-pipe are disposed of, preferably, by conducting them to the ash-pit of a stove or furnace and there causing them to pass through the grate into a fire upon the grate, where they are consumed and facilitate the combustion.

10 Fig. I of the drawings shows a furnace *i*, and *j* designates the combustion-chamber of the furnace, *k* the grate, and *l* the ash-pit below the grate. A pipe *m* has its discharging end arranged within the ash-pit in suitable proximity to the under side of the grate and extends from the furnace to the top of the tank *a*, where it is in open relation with the chamber of the said tank. Preferably the waste-pipe *g* communicates with the chamber 15 of the tank *a* at an elevation somewhat below the inlet of the pipe *m*, so that there is no liability of water entering the pipe *m*, which extends, preferably, somewhat above the tank. Any gases and vapors or air received 20 within the tank *a* and not carried off in solution with the water flowing from the said tank are conducted from the tank by the pipe *m* to the furnace for consumption.

The means employed for introducing the 30 gases and vapors which are to be disposed of into the chamber of the tank *a* comprises, preferably, a perforated pipe-section *n*, arranged horizontally within the lower portion of and in close proximity to the bottom of 35 the said chamber. The pipe-section *n* is supported in any approved manner and extends, preferably, through one end wall of the tank *a* to near the inner surface of the other end wall of the tank, being closed at its inner end, 40 as at *o*, and attached at the said end, as at *p*, to the adjacent end wall of the tank by a bolt and a nut or other fastening device, so as to steady the said pipe-section during the operation of the apparatus. The pipe-section *n* 45 has its lower portion provided with a plurality of series of orifices *r*, with each series arranged longitudinally of the pipe-section and a suitable distance apart laterally and with the orifices of each series arranged at short 50 intervals longitudinally of the pipe-section. The pipe-section *n* is connected and in open relation at its outer or receiving end with the discharging end of a valved pipe *s*, which connects and is in open relation with the outlet 55 of a suitably-operated pump *t*, which is arranged at an elevation below the tank *a*. The pipe *s*, outside of and next adjacent to the tank *a*, has a convolution *u* arranged in a vertical plane and extending preferably 60 above the tank *a*, or at least above the water-level maintained within the tank during the operation of the apparatus, so that water cannot be conducted from the tank through the said pipe *s*. The inlet of the pump *t* is connected and in open relation with the valved 65 pipe *v*, which extends from and is in open relation with the chamber of a drier or render-

ing or reducing apparatus or any vessel or receptacle *x*, containing or supplied with gases and vapors which are to be disposed of without contamination of the external atmosphere. The valves *q* of the pipes *v* and *s* are of course opened, if not already open, preparatory to the operation of the pump *t*.

It will be observed that the location of the 75 perforated pipe-section *n* in close proximity to the bottom of the chamber of the tank *a* is important, because thereby the gases and vapors are introduced into the body of water within the said chamber farthest below the 80 outlets of the chamber, and any soluble gaseous or aeriform body passing into the said body of water will likely have been absorbed or diffused in the water before it reaches the said outlets, so that only gases and air not 85 soluble in water will pass from the tank into the pipe which conducts the said last-mentioned gases and air to the furnace. It will be observed also that the pumping of the 90 gases and vapors and accompanying air into 95 the tank *a* and any suction created by a draft through the furnace materially expedite or facilitate the passage of gases to the furnace. I would also remark that a trap *g'* is provided at the junction of the waste-pipe *g* with the 95 said sewer-feeding pipe *h*, so as to form a liquid seal which will effectually prevent the 100 passage into the sewer *h* of any gases which escape into the said pipe *g* without entering into solution with the said water passing into the said pipe *g*, and hence it will be observed that gases and vapors not entering into solution with the water in the tank *a* cannot escape passage to the furnace.

What I claim is—

Apparatus of the character indicated, comprising a tank having an outlet at the top for any gaseous or aeriform fluid not soluble in water, a valved water-supply pipe communicating with the chamber of the tank at the 11 bottom of the tank, a perforated pipe-section arranged within and near the bottom of the said chamber and extending longitudinally of the tank, a pipe for conducting gases and vapors to the tank and in open relation with the said perforated pipe-section, a sewer-feeding pipe arranged a suitable distance below the tank, an upright pipe or passage-way in open relation at one end with the said sewer-feeding pipe and communicating at its opposite end with the upper portion of the aforesaid chamber, and a valved drain-pipe communicating with the aforesaid chamber at the bottom of the tank and discharging into the aforesaid upright pipe.

In testimony whereof I sign the foregoing specification, in the presence of two witnesses, this 8th day of January, 1902, at Cleveland, Ohio.

EUGENE R. EDSON.
